GEORGE C. GUCKES, OF LAKEWOOD, OHIO

CUSHIONING FEET FOR SINK STRAINERS

Application filed May 31, 1932. Serial No. 614,538.

This invention relates to cushioning feet for metal sink strainers and more particularly, to cushioning feet which are adapted to be connected, by simple snap fastening means, to the perforated bottoms of such strainers, regardless of whether said strainers are new or old ones. By the use of the present cushioning feet, which housewives and the like can readily attach to their present metal sink strainers, there is effectively avoided the chipping of the enamel of metal sink strainers, the noise of moving such strainers about in kitchen sinks, and the discoloration, etc., of the enamel of said sinks by such strainers.

Inasmuch as metal sink strainers frequently vary in thickness, due to the thickness of the metal of which they are made and/or to the thickness of their enamel coatings, the snap fastening means of the present cushioning feet are of adjustable character, thereby enabling said feet to be firmly and properly connected to the perforated bottoms of practically all sink strainers now on the market, regardless of the thickness of said bottoms.

Some metal sink strainers now on the market have their perforated bottoms provided with depending supporting portions of generally convex form, (which portions, incidentally, are usually the parts from which the enamel is first chipped) and in order to enable the present cushioning feet to be properly connected to such portions, the upper ends of said feet are of concave form, the curvature thereof corresponding to the curvature of said strainer convex supporting portions. The concave upper ends of the present cushioning feet do not, however, interfere in any way with their connection to flat portions of sink strainer bottoms, as will hereinafter more fully appear.

Further features of the present invention are in part obvious and in part will appear more in detail hereinafter.

The invention will be readily understood from the following description of two forms thereof, reference being had to the accompanying drawing in which

Fig. 1 is a side elevation of a metal sink strainer having a set of the present cushion-

ing feet connected thereto; Fig. 2 is a vertical sectional view of a portion of a metal sink strainer with the parts of one form of one of the present cushioning feet shown in spaced relation thereto, in sort of a pre-assembly position; Fig. 3 is a view similar to Fig. 2 but showing said foot parts attached to said strainer portion; Fig. 4 is a detail cross-sectional view of said form of foot, the view being on the line 4-4, Fig. 3; Fig. 5 is a view similar to Fig. 3 but showing said form of foot connected to a sink strainer portion of greater thickness; and Fig. 6 also is a view similar to Fig. 3 but showing a modified form of foot connected to a portion of a metal sink strainer of a slightly different type.

Two types of metal sink strainers are shown in the accompanying drawing, one type being shown in Figs. 1, 2, 3 and 5 and the other type being shown in Fig. 6. Both types are quite common and each includes perforated side walls 1 (usually three) and a perforated bottom 2 integral therewith. Due to the thickness of the metal of which they are made and/or to the thickness of the enamel with which they are coated, metal sink strainers frequently vary in thickness and in the accompanying drawing there is shown in Fig. 5 a sink strainer having a considerably greater thickness than those shown in Figs. 2, 3 and 6.

As best shown in Fig. 2, each of the present cushioning feet comprises a suitable cushioning foot member 5, of rubber or the like and of generally cylindrical shape, and simple snap fastening means for readily and easily connecting said foot member to the perforated bottom of a metal sink strainer.

The snap fastening means for each cushioning foot comprises two cooperating fastening parts, namely, a socket-like part suitably assembled with the foot member 5 of said foot and a suitable stud part adapted to be connected to a metal sink strainer by being extended through one of the perforations in the bottom thereof, the lower portion of said stud part being adapted for connection to said socket-like fastening part.

The two parts of said snap fastening means are therefore adapted to be connected to each

other with the perforated bottom of a sink strainer therebetween, as will be readily understood.

For the purpose of enabling the present cushioning feet to be properly connected to sink strainers of varying thickness, the fastening stud parts of the present feet are adapted for adjustable connection to the socket-like fastening parts thereof, as will 10 hereinafter more fully appear.

The socket-like fastening part of the snap fastening means for each of the present cushioning feet is in the form of a sheet metal disc 10 provided with a centrally disposed, diametrically extending slot 11 enlarged at its 15 middle to provide a generally circular opening 12 for receiving the lower end portion of a fastening stud part. As clearly shown in the accompanying drawing, each cushioning 20 foot member 5 is provided with a centrally disposed, vertically extending passageway 15 to receive the lower end portion of a fastening stud part and suitably embedded in the rubber or other material of each such foot 25 member, at substantially the middle of the passageway 15 thereof, is one of said fastening discs 10, said disc being arranged transversely of said passageway with the disc 30 opening 12 at substantially the central, longitudinal axis thereof.

Two types of fastening stud parts are shown in the accompanying drawing, one type being shown in Figs. 2 to 5 inclusive and the other type being shown in Fig. 6, 35 both types of said stud parts being adapted for adjustable connection to a fastening disc part 10.

The type of stud part shown in Figs. 2 to 5 inclusive is probably the preferred one 40 and said stud part includes a generally cylindrical shank 20 provided at its upper end with a generally flat, substantially circular head 22. The lower portion of said shank is provided with a series of annular fastening 45 grooves 24, one arranged above the other, there being three such grooves in the present stud part.

The stud part shown in Fig. 6 has a shank 27 in the form of a generally U-shaped spring 50 metal member, the lower portions thereof being bent back and forth to provide three pairs of locking grooves 28. Suitably secured to the upper ends of said shank member is a generally flat, substantially circular head 55 29.

To connect or attach to the perforated bottom of a metal sink strainer any one of the present cushioning feet, the cushioning foot member 5 thereof, with a fastening disc part 60 10 suitably embedded therein, is placed beneath one of the perforations in said sink strainer bottom, and the shank of the stud fastening part for said foot is then pushed down through said strainer bottom perforation 65 into the passageway 15 of the foot mem-

ber therebelow. The grooved lower portion of the shank of said stud part enters the opening 12 of the fastening disc part 10 of said cushioning foot member, and the downward movement of said stud part is continued until its head at its upper end engages the upper surface of said sink strainer bottom. Depending upon the thickness of the sink strainer bottom, such engagement of the stud part head with the sink strainer bottom finds one of the three grooves of the shank of said stud part lying within the opening 12 of the disc 10 of the cushioning foot member, such as the lowermost groove, Fig. 5, in the case of an exceptional thick strainer, or a middle groove, Figs. 3 and 6, in the case of sink strainers of average thickness.

Some metal sink strainers now on the market have their perforated bottoms provided with depending perforated supporting portions of generally convex form, such as the supporting portions 30 of the sink strainers of Figs. 1, 2, 3 and 5. To enable the present cushioning feet to be properly secured to such convex strainer supporting portions, as well as to flat portions of the strainer bottoms, each foot member 5 of the present cushioning feet has a concave upper end 32, the curvature of which preferably corresponds to the curvature of said strainer supporting portions 30. Said concave upper ends do not interfere, however, with the connection of the present feet to flat strainer bottoms, as in Fig. 6, for example.

What I claim is:

1. In combination with a metal sink strainer having a perforated bottom, a set of supporting feet for said strainer, each of said feet comprising a strainer supporting member and a connecting member for maintaining said supporting member in assembled relation with said strainer bottom, said supporting member being provided with a snap fastener part and said connecting member having a shank portion and a headed portion at the upper end of said shank portion, said shank portion but not said headed portion being of such size as to enable it to be extended down through one of the perforations of said strainer bottom and said shank portion being provided with snap fastening means for snap fastening connection to the snap fastener part of said supporting member, whereby the supporting members of said set of supporting feet may be maintained in assembled relation with said strainer bottom by the connecting members of said set of feet, with said strainer bottom confined between said supporting members and the headed portions of said connecting members.

2. In combination with a metal sink strainer having a bottom provided with convex depending projections each having a perforation therein, a set of supporting feet for said strainer, each of said feet comprising

- a strainer supporting member and a connecting member for maintaining said supporting member in assembled relation with said strainer bottom, said supporting member 5 having a concave upper end and being provided with a snap fastener part, the concave upper end of said supporting member enabling it to be properly maintained in assembled relation with a convex depending projection of said sink strainer bottom, said connecting member having a shank portion and a headed portion at the upper end of said shank portion, said shank portion but not said headed portion being of such size 10 as to enable it to be extended down through the perforation of one of the projections of said strainer bottom and said shank portion being provided with snap fastening means for snap fastening connection to the snap fastener part of said supporting member, whereby the supporting members of said set of supporting feet may be maintained in assembled relation with said strainer bottom by the connecting members of said set of feet, with said strainer bottom confined between said supporting members and the headed portions of 15 said connecting members. 20 3. In combination with a metal sink strainer having a perforated bottom, a set of supporting feet for said strainer, each of said feet comprising a strainer supporting member and a connecting member for maintaining said supporting member in assembled relation with said strainer bottom, said supporting member being provided internally with a snap fastener part and with a passageway providing access to said part, said connecting member having a shank portion and a headed portion at the upper end of said shank portion, said shank portion but not said headed portion being of such size as to enable it to be extended down through one of the perforations of said strainer bottom into the passageway of said supporting member, said shank portion being provided with a plurality of vertically spaced annular grooves each adapted for snap fastening connection to the snap fastener part of said supporting member, whereby the supporting members of said set of supporting feet may be maintained in assembled relation with said strainer bottom by the connecting members of said set of feet, with said strainer bottom confined between said supporting members and the headed portions of said connecting members. 25 4. In combination with a metal sink strainer having a perforated bottom, a set of supporting feet for said strainer, each of said feet comprising a strainer supporting member and a connecting member for maintaining said supporting member in assembled relation with said strainer bottom, said supporting member being provided with a snap fastener part and said connecting member having a shank portion and a headed portion 30 at the upper end of said shank portion, said shank portion but not said headed portion being of such size as to enable it to be extended down through one of the perforations of said strainer bottom and said shank portion being provided with a plurality of snap fastening means for adjustable snap fastening connection to the snap fastener part of said supporting member, whereby the supporting members of said set of supporting feet may be maintained in assembled relation with said strainer bottom by the connecting members of said set of feet, with said strainer bottom confined between said supporting members and the headed portions of 35 said connecting members. 5. In combination with a metal sink strainer having a perforated bottom, a set of supporting feet for said strainer, each of said feet comprising a strainer supporting member of cushioning material and a connecting member for maintaining said supporting member in assembled relation with said strainer bottom, said supporting member being provided internally with a generally horizontally disposed snap fastener part and with a generally vertically disposed passageway providing access to said part, said connecting member having a shank portion and a generally flat headed portion at the upper end of said shank portion, said shank portion but not said headed portion being of such size as to enable it to be extended down through one of the perforations of said strainer bottom into the passageway of said supporting member, said shank portion being provided with a plurality of vertically spaced annular grooves each adapted for snap fastening connection to the snap fastener part of said supporting member, whereby the supporting members of said set of supporting feet may be maintained in assembled relation with said strainer bottom by the connecting members of said set of feet, with said strainer bottom confined between said supporting members and the headed portions of said connecting members. 40 6. In testimony whereof I hereby affix my signature.
